PREPARATION OF AMMONIUM
METAVANADATE

Andrew D. Kelmers, Newport Beach, Calif., assignor to
Union Carbide Corporation, a corporation of New
York

No Drawing. Original No. 3,063,796, dated Nov. 13,
1962, Ser. No. 93,014, Mar. 3, 1961. Application for
reissue July 26, 1963, Ser. No. 299,139

4 Claims. (Cl. 23—51)

Matter enclosed in heavy brackets [ ] appears in the
original patent but forms no part of this reissue specifica-
tion; matter printed in italics indicates the additions
made by reissue.

The present invention pertains to the production of pure
ammonium metavanadate. More particularly, the present
invention pertains to a process for production of pure
ammonium metavanadate directly from acidic solvent ex-
traction strip solutions in a single precipitation step.

Vanadium extraction from the mother ore commonly
is initiated by acid leaching vanadium bearing ore in a
sulfuric acid leach solution. The resulting leach liquor
is classified by countercurrent decantation to produce a
clear leach liquor substantially void of entrained solids
and slimes. Vanadium is present in the leach liquor as
vanadyl sulfate. Vanadium is removed from the leach
liquor by solvent extraction techniques utilizing di(2-
ethylhexyl)phosphoric acid organic extractant for ex-
ample. The loaded organic extractant is then stripped by
a sulfuric acid strip solution. Vanadium passes from
the organic extractant to the acidic strip solution as vanadyl
ion (VO^{+2}). The strip solutions commonly con-
tain 10–15 percent sulfuric acid and about 6 to 10 percent
vanadium pentoxide as vanadyl ion along with other
impurities such as iron, alumina, phosphates and arsenates.

The strip solution is then oxidized with sodium chlorate
and partially neutralized with sodium carbonate to pre-
cipitate an intermediate sodium polyvanadate containing
the above impurities. This product is termed "red cake"
due to its characteristic color.

To obtain pure vanadium pentoxide, the precipitate is
redissolved in hot ammonium hydroxide and the solution
is thickened and filtered to remove hydrated impurities.
The clear solution containing vanadium is then treated
with ammonium chloride to precipitate ammonium meta-
vanadate which is fused to vanadium pentoxide, the de-
sired final product.

The above-described prior art process realizes about 70
percent recovery of vanadium while requiring numerous
steps.

It is an object of the present invention to provide a
process for the direct recovery of essentially pure am-
monium metavanadate from acidic organic solvent ex-
traction stripping solutions.

It is another object to provide a process for direct
recovery of ammonium metavanadate containing as high
as 90 percent of the vanadium in the mother ore treated.

It is a further object to provide a process by which
the precipitated impurities are readily filtered.

It is still a further object to provide a process for the
production of ammonium metavanadate of very high
purity.

Further objects will be apparent from the remaining
disclosure and the appended claims.

The process which accomplishes the aforementioned
objects comprises providing an acidic vanadyl solution
containing at least one of the impurities iron, alumina,
phosphate or arsenate; providing an aqueous solution of
sodium chlorate and sodium carbonate and adding said
acidic vanadyl solution to said aqueous sodium chlorate-
sodium carbonate solution and simultaneously oxidizing

vanadium to the pentavalent state and neutralizing the
solution; digesting the solution for a period of time suf-
ficient to maintain vanadium in solution and to allow
precipitation of impurities; filtering the precipitated im-
purities from the solution; adding at least one compound
selected from the group consisting of ammonium chloride
and ammonium sulfate to the solution to precipitate am-
monium metavanadate and removing the vanadium com-
pound from the solution.

10 It is essential that the vanadyl solution be added to the
sodium chlorate-sodium carbonate solution to minimize
precipitation of sodium polyvanadate of tetravalent vanad-
ium and to prevent excess foaming due to the evolution
of carbon dioxide. The sodium chlorate oxidizes some
15 of the impurities thereby aiding in their precipitation as
the solution neutralizes.

In this manner, the impurities are selectively precipi-
tated from the strip solution without loss of vanadium.

During addition of the strip solution to the sodium
20 chlorate-sodium carbonate solution there may be some
minor amount of precipitation of tetravalent vanadium
before sodium chlorate causes oxidation of vanadium to
the pentavalent state. The solution is digested at a tem-
perature ranging from 70 to 90° C. for a period of time
25 sufficient to oxidize and solubilize any vanadium com-
pounds which may have precipitated and essentially to
allow the complete precipitaion of the impurities in a
readily filterable form.

The incidental precipitation of small amounts of van-
30 adium during oxidation and neutralization in the present
process is distinguished from the formation of large quan-
tities of the polyvanadates of tetravalent vanadium which
precipitates when the sodium carbonate-sodium chlorate
solution is added to the vanadyl solution. After digestion
35 the solution is filtered to remove the precipitated im-
purities. The resulting filtrate is a substantially clear solu-
tion of pentavalent vanadium ($NaVO_3$) being light yellow
in color.

The amount of sodium chlorate required is dependent
40 to some extent upon the type and amount of impurities
present and the extent to which they will consume the
oxidizer. A sufficient amount of sodium chlorate is re-
quired to at least oxidize substantially all the vanadium
in the strip solution to the pentavalent state. Preferably,
45 in some instances it is desired to add an excess of
sodium chlorate up to about 120 percent of the amount
stoichiometrically required to oxidize all the vanadium
to the pentavalent state. The excess oxidizer will aid in
50 precipitation of the impurities although substantial re-
moval of impurities is achieved without oxidation of the
same with sodium chlorate.

Sodium carbonate is added in amounts sufficient to
neutralize the solution to a pH of about 7.0. Preferably
55 in some instances it is desired to add an excess of sodium
carbonate up to about 130 percent of the amount stoichio-
metrically required to neutralize the solution to a pH of
about 7.0.

A temperature of 80° C. is considered the optimum
60 temperature during digestion. A period of one hour is
approximately the desired digestion period although the
extent of the digestion period may be affected by the type
of impurities, the ease with which a filterable impurity
precipitate is obtained and the amount of tetravalent van-
65 adium compounds which may happen to precipitate dur-
ing addition of sodium carbonate and sodium chlorate to
the acidic strip solution.

Ammonium chloride and/or ammonium sulfate is added
70 to the filtrate to precipitate pure ammonium metavan-
adate. Sufficient ammonium chloride or sulfate is used
to achieve substantially quantitative precipitation of the
vanadium. Precipitation should be carried out at 30°

C. or cooler to minimize reagent consumption and may require one or more hours to come to completion.

The precipitate is washed to dilute ammonium chloride or water, for example, to remove any residual sulfate solution and calcined at a temperature ranging from 800 to 900° C. in accordance with well known techniques to produce vanadium pentoxide of high purity.

The barren solution remaining after precipitation may be recycled for use as make-up water in the leaching or countercurrent decantation circuits.

The following example is illustrative of present process.

Three portions of acidic vanadyl sulfate stripping solution resulting from the sulfuric acid stripping of an organic solvent extractant and containing iron, alumina, phosphates and arsenates were respectively added to aqueous solutions containing 100 percent of the stoichiometric amount of sodium carbonate required to neutralize the strip solution irrespective of the amount of sodium carbonate required to precipitate the impurities and 130 percent of the stoichiometric amount of sodium chlorate required to oxidize the vanadium in said stripping solution to pentavalent vanadium. A slurry was formed upon precipitation of the impurities. The slurry was digested for one hour at a temperature of 80° C. and filtered, to remove the impurity precipitate. The resulting clear vanadium bearing solution was mixed with sufficient ammonium chloride and allowed to stand at 25° C. to cause precipitation of ammonium metavanadate. After a period of about 1 to 2 hours the vanadium had substantially precipitated as ammonium metavanadate. The ammonium metavanadate was separated from the barren strip solution and washed with a 5 percent solution of ammonium chloride and dried. The results are tabulated below:

PERCENT DISTRIBUTION OF V₂O₅

Test	In the Impurity Cake, Percent	In the Barren Strip Solution, Percent	Ammonium Metavanadate, Percent Recovery of Total in Mother Ore
A-----	2.09	5.15	91.0
B-----	1.96	5.03	89.6
C-----	2.11	5.18	91.3
Average-----	2.05	5.42	90.6

REAGENT CONSUMPTION

	Lbs./lb. V ₂ O ₅ recovered
Na ₂ CO ₃ -----	3.32
NaClO ₃ -----	0.26
NH ₄ Cl -----	1.45

V₂O₅ ACCOUNTABILITY

	Percent of V ₂ O ₅
Loss to impurity cake -----	2.1
Loss to barren strip solution -----	5.4
Ammonium metavanadate -----	90.6
Total -----	98.1

The ammonium metavanadate produced was extremely pure with respect to alkali metal contamination. No sulfate or phosphate was detected chemically. Spectrographic analyses show .05-.1% Fe, 0.005-.02% Na and .01%-.02% Si plus a trace of copper as the only contaminants.

What is claimed is:

1. A process for the production of substantially pure ammonium metavanadate from acidic vanadyl solutions containing at least one of the impurities iron, alumina, phosphate and arsenates comprising providing a solution containing sodium chlorate and sodium carbonate, said

sodium chlorate being present in amounts at least sufficient to oxidize substantially all the vanadium in said vanadyl solution to the pentavalent form and said sodium carbonate being present in amounts sufficient to adjust the pH of said acidic vanadyl solution to about 7.0; adding said acidic vanadyl solution to said solution containing sodium carbonate and sodium chlorate; digesting said solution at a temperature ranging from 70 to 90 degrees centigrade for a period of time sufficient to sustain vanadium in solution and to allow precipitation of said impurities; filtering the precipitated impurities from said solution; adding to said solution at least one compound selected from the group consisting of ammonium chloride and ammonium sulfate to cause precipitation of substantially pure ammonium metavanadate; and removing said ammonium metavanadate from said solution.

2. A process for the production of substantially pure ammonium metavanadate from acidic vanadyl solutions containing at least one of the impurities iron, alumina, phosphates and arsenates comprising providing a solution containing sodium chlorate and sodium carbonate, said sodium chlorate being present in amounts ranging from 100-[110] 130 percent of the stoichiometric amount of sodium chlorate required to oxidize the vanadium of said vanadyl solution to pentavalent vanadium and said sodium carbonate being present in amounts ranging from [110] 100 to 130 percent of the stoichiometric amount required to adjust the pH of said acidic vanadyl solution to about 7.0; adding said acidic vanadyl solution to said solution containing sodium chlorate and sodium carbonate; digesting said solution at a temperature ranging from 70 to 90 degrees centigrade for a period of about 1/2 to 2 hours to sustain vanadium in solution and to allow precipitation of said impurities; filtering the precipitated impurities from said solution; adding to said solution at least one compound selected from the group consisting of ammonium chloride and ammonium sulfate to cause precipitation of substantially pure ammonium metavanadate; and removing said ammonium metavanadate from said solution.

3. A process for the production of substantially pure ammonium metavanadate from acidic vanadyl solutions containing at least one of the impurities iron, alumina, phosphates and arsenates comprising providing a solution containing sodium chlorate and sodium carbonate said sodium chlorate being present in amounts ranging from 100-[110] 130 percent of the stoichiometric amount of sodium chlorate required to oxidize the vanadium of said vanadyl solution to pentavalent vanadium and said sodium carbonate being added in amounts ranging from [110] 100 to 130 percent of the stoichiometric amount required to adjust the pH of said acidic vanadyl solution to about 7.0; adding said acidic vanadyl solution to said solution containing sodium chlorate and sodium carbonate; digesting said solution at a temperature of about 80° C. for a period of about 1 hour; filtering said solution; adding to said solution at least one compound selected from the group consisting of ammonium chloride and ammonium sulfate to cause precipitation of substantially pure ammonium metavanadate; and removing said ammonium metavanadate from said solution.

4. A process in accordance with claim 3 wherein said precipitation is conducted in a solution maintained at ambient temperature.
